UNITED STATES PATENT OFFICE.

ABRAHAM B. SCHAPIRO, OF NEW YORK, N. Y.

DESIGN FOR A HATPIN OR SIMILAR ARTICLE.

Application filed April 12, 1923. Serial No. 5,800. Term of patent 3½ years.

To all whom it may concern:

Be it known that I, ABRAHAM B. SCHAPIRO, a citizen of the United States, residing at the city of New York, in the county of Bronx and State of New York, have invented a new, original, and ornamental Design for Hatpin or Similar Article, of which the following is a specification, reference being had to the accompanying drawing, forming part thereof.

My invention contemplates the provision of a hat pin or similar article to simulate a golf stick, with brilliants set in the head and handle and surface ornamentation engraved or cast on one of the faces of said article.

I claim:

The ornamental design for a hatpin or similar article as shown and described.

ABRAHAM B. SCHAPIRO.
